Edward Quincy Norton.

UNITED STATES PATENT OFFICE.

EDWARD QUINCY NORTON, OF MOBILE, ALABAMA.

DEVICE FOR BEATING OUT PIANOS.

SPECIFICATION forming part of Letters Patent No. 393,024, dated November 20, 1888.

Application filed September 23, 1887. Serial No. 250,962. (No model.)

To all whom it may concern:

Be it known that I, EDWARD QUINCY NORTON, a resident of Mobile, in the county of Mobile and State of Alabama, have invented a 5 new and useful Improvement in Devices for Beating out Pianos, of which the following, taken in connection with the accompanying drawings, is a specification.

My invention relates to beating-out machines for pianos; and the objects of my improvement are to beat out any inequalities in the cloth, felt, and leather throughout the action, to stretch and settle the strings with uniformity and rapidity, and to develop at once 10 any existing latent defects which cannot be detected by methods now employed until actual use through a considerable time. I attain these objects by the mechanism illustrated in the accompanying drawings, in which—

20 Figure 1 is a top plan of a portion of the machine adjusted on a piano. Fig. 2 is a longitudinal section of the end of the clamp. Fig. 3 is a side elevation of the clamp with the beater-rail spring and lifter-rail.

25 1 is a clamp, which may be made of wood or metal, as may be desired; and it consists of a vertical piece, 2, on the inner face of which is the felting, 3.

30 4 and 5 are horizontal arms fixed on the vertical piece 2. When cast of metal, the arms and vertical piece may be cast together as a whole. Through the lower arm, 5, pass the threaded clamp-screws 6 and 7, the said arm 5 having the holes 8 and 9, provided with corresponding 35 threads to engage with the thread on screws 6 and 7. The upper arm, 4, has two holes, 10 and 11, threaded so that the adjusting-screws 12 and 13 may operate therein. Each screw has fixed at its end the flat washer 14, which 40 may be felted, so that the surface with which they come in contact may not be injured. At the outer end of the arm 4 is the opening 15, in which is adjusted the rounded end 17 of the lifting-rail 16, which is allowed to rotate in 45 said opening.

50 18 is a triangular recess in the inward end of the arm 4, in which is adjusted the beater-rail 19. The end 20 of said rail 19 is rounded, and is adjusted in the orifice 21 of the arm 4, 55 in which it is allowed to turn when desired, as hereinafter mentioned. The said end 20 is

kept from any lateral movement by the pin 23, or by any suitable method.

22 is the rail-screw passing through the arm 4, and pressing against the rail 19 in the recess 18.

24 is the beater-spring, which at one end is fixed by screws 25, or any suitable mechanical device, to the under side of the rail 19, and at the other end is slightly upbent, as shown in 60 Fig. 3.

26 is the beater, made of any suitable form or material, covered with felt, and fastened on the spring 24 by screws or any suitable mechanical contrivance.

65 The clamp 1, which has been described and shown in Fig. 3, as may be readily observed, is the clamp used at the left of my machine. A similar clamp is used at the right or upper end constructed with similar parts, which are, 70 however, arranged on the inner face, as in the left clamp—that is, the one is a clamp for the right side or end, the other a clamp for the left side.

75 16 is the lifting-rail, which has two rounded ends, 17 17, adjusted, as described, in the arms 4 4 of the clamps 1 1. On either end of the said lifting-rail 16, outside of the arm 4, is fixed the grooved wheel 28, and upon the wheel is the fixed handle 29, their function being to turn 80 said rail 16. The said rail 16 is twisted, as shown in Fig. 3, to allow the beaters 26 to fall successively on the keys of the piano.

85 The rail 19 is triangular in shape, with rounded edges, and arranged in the recesses 18 18, as described. The springs 24 are placed along the rail 19, as shown in Fig. 3, at a distance corresponding to the distance between the piano-keys, and have their upturned ends resting on the rail 16. When it is desired to 90 increase the striking-power of the springs 24, the rail 19 is turned downward in the recesses 18 18 by the rail-screws 22.

95 30 are piano-keys of the ordinary pattern.

When it is desired to operate my machine, 95 the arms 4 4 are adjusted on the key-cheeks or key-bed of the piano, as shown in Fig. 1, and the arms 5 5 on the under part of the piano-case. By means of the adjusting-screws 12 and 13 the height of the machine to the key-board is adjusted so that it may be applicable to any piano. The clamps 1 1 are then fixed

in position by turning the clamp-screws 6 and 7 against the under part of the piano. When the clamps are thus fixed, the beaters 26 are above the respective keys, as shown in Fig. 1, 5 ready to strike where the fingers would ordinarily touch, the beaters above the white keys being necessarily farther outward on their respective springs than those above the black keys. The lifting-rail 16 is turned, as indicated by arrow in Fig. 3, by means of the handle 29, or by a belt over the wheel 28. The beater-springs 24, which rest on the rail 16, are raised as the twist in said rail allows, the time of the raising and falling of the said 15 springs being dependent on the twist. The twist is such that the beaters shall depress the keys successively, and thus each note played in its turn. I do not confine myself to one twist, as it may be varied to allow the beaters 20 to depress the keys in different order. When the springs 24 fall, they carry with them the beaters 26, which strike the keys in their successive order, according to the twist.

It will thus be observed that by my machine 25 all defects or inequalities in mechanism and material of the action can be developed in the shortest possible time, thus admitting of the final regulating or adjusting of the action. The stretch of the strings of the piano is also beaten out, and the strings may receive their 30 final tuning, thus "aging" the piano, which can then with safety be termed complete and suitable for sale.

Having described my invention and its operation, what I desire to secure by Letters Patent, and claim, is—

1. In combination, the clamps 1 and the lifting-rail 16, twisted as described, and having the

ends rounded and adjusted in the arms 4 4 of said clamps 1, all substantially as described, 40 and for the purpose specified.

2. The lifting-rail 16, having the rounded ends 17 17, and twisted as described, substantially as and for the purpose specified.

3. In combination, the beater-rail 19, the beater-springs 24, fixed to said rail, and the beaters 26, fixed to said springs 24, all substantially 45 as described and shown.

4. In combination, the clamps 1, the clamp-screws 6 and 7, operating in the holes 8 and 9 50 of the arms 5 of said clamps, the adjusting-screws 12 and 13, operating in the holes 10 and 11 of the arms 4 of said clamps, the beater-rail 19, adjusted in the recesses 18 of said clamps and allowed to turn upon the ends 20, adjusted 55 in the orifices 21 of the arms 4, the rail-screws 22, passing through said arms 4 and against said rail 19, the beater-rail 16, twisted as described, having the rounded ends 17, passing through said arms 4, and having thereon the wheels 28, provided with the handle 29, for the purpose of turning said beater-rail, the beater-springs 24, fixed on the under side of rail 19 by the screws 25, and having their opposite ends upturned and resting on the lifting-rail 16, and the beaters 26, fixed to said spring as described, all arranged substantially as described and shown.

In testimony whereof I have signed my name to this specification, in the presence of two subscribing witnesses, on this 23d day of September, A. D. 1887.

EDWARD QUINCY NORTON.
